BY HIS ATTORNEY Lewis J. Doolittle.

UNITED STATES PATENT OFFICE.

FREDERICK A. CLEVELAND, OF NEW YORK, N. Y.

BINDER.

No. 829,323.

Specification of Letters Patent.

Patented Aug. 21, 1906.

Application filed July 7, 1905. Serial No. 268,662.

To all whom it may concern:

Be it known that I, FREDERICK A. CLEVELAND, a citizen of the United States, and a resident of New York, in the county of New York and State of New York, have invented 5 certain new and useful Improvements in Binders, of which the following is a specification.

This invention relates to a device which 10 may be applied to binders of the loose-leaf type, the object being to provide a device of simple construction which may be used in connection with covers or binders of this class, which may be easily operated, and 15 which will be positive in its action.

The use of binders of this description is well understood, and it is not thought necessary to enter into an explanation of their operation further than to state the principal requirement, which is that any number of pages 20 or leaves may be inserted, replaced, or taken out without disturbing the remaining leaves.

The object of my invention is to provide a device which shall meet this requirement and 25 accomplish the desired result by the use of a simple locking mechanism which does not require separate keys or other devices to operate the same and which shall be self-contained and operated by turning the book on one 30 side to lock the covers in any desired position and to release the same by simply reversing the position of the book. To accomplish this result, I provide an upper and lower clamping-section which may be attached to 35 the covers of the binder. These clamping-sections are normally held apart by the action of springs contained in telescoping members attached to said clamping-sections in the usual manner. Attached to one of these 40 clamping-sections, preferably the upper, I provide a post which carries a pawl or dog which is adapted to engage projections on the interior of a coöperating post or casing which is secured to the lower clamping-section. 45 This latter post or casing is adapted to telescope over the post carrying the pawl or dog. The construction of these parts is such that when the clamping-sections are in the position shown in the drawings a free inward movement is permitted and the pawl or dog will operate to prevent an outward movement of the members. As the position of the 50 covers is reversed, the pawl or dog will drop out of engagement with the outer casing into 55 an inoperative position, allowing the clamping-members to be separated by the action of

the springs heretofore referred to or by other suitable means.

The construction and operation of the device will be more fully explained in connection with the drawings accompanying this specification.

Figure 1 is a perspective side elevation of a pair of clamping-sections, or binder-frames with the covers and leaves of the book omitted. Fig. 2 is an enlarged side elevation in section of the post and casing carrying the locking mechanism. Fig. 3 is an enlarged side elevation and detail view showing the end view of the pawl or dog in position at the lower end of the post carrying the same as in Fig. 2. Fig. 4 is an enlarged side elevation in section of the post and casing, showing a modification of the locking mechanism. Fig. 5 is an enlarged side view of the lower end of the post carrying the pawl or dog shown in Fig. 4.

In Fig. 1 at 1 and 2 is shown an upper and lower clamping-section, respectively, which may be attached by any suitable means to the covers of the binder; or, if preferred, the covers themselves may form the clamping-sections and have the locking device attached directly thereto.

At 3 3 are shown telescoping members containing springs which operate normally to separate the clamping-sections 1 and 2.

At 4 is shown a post which may be attached to the upper clamping-section 1 by any suitable means and preferably in such a manner that it may be rotated therein. This may be accomplished by socketing the upper end of the post in the clamping member 1, as shown, and holding the same in position by means of an ordinary flat-head screw. This screw may be secured in the post 4 by any suitable means, and by using an ordinary screw-driver in the slot thereof the post may be readily rotated in its socket.

At the lower end of the post 4 may be provided a slot in which a sliding pawl, such as 5, as shown in the construction illustrated by Fig. 2, is carried. This pawl has an opening or slot therein, such as 5', which is of such a shape and size as to permit a limited movement of the pawl 5 on either side of the retaining-pins 6 and 6'.

The lower end of the slot in the post 4 is provided with a beveled surface or wall 7, upon which the pawl 5 is operated by gravity into or out of engagement with the inner surface of the casing 8. The pawl 5 is not at-

tached or fixed in position in the slot in the post 4, but is retained therein and limited in its movement by means of the pins 6 and 6'. The outer edge of the pawl 5 is provided with 5 one or more projections which are adapted to engage corresponding projections on the interior of the casing 8 when the members stand in the position shown in the drawings.

When the position of the covers and attached parts is reversed, the pawl 5 will drop back by gravity out of engagement with the casing 8 and allow the parts to be separated, as already described.

The casing 8 may be secured to the lower 15 clamping member 2 by any suitable means, such as by threading the same therein, as shown, or otherwise.

Referring to Figs. 4 and 5, a pawl 9 of somewhat different construction is shown. The 20 recess in the lower end of the post 4' has the inner surface thereof, against which the pawl 9 rests, formed at slight angle with the center line of the post 4' and is also curved outwardly, so as to throw the pawl into engagement with the projections on the inner surface of the casing 8' when the parts stand in the position shown in the drawings, in which position gravity operates to move the pawl to the lower end of the recess.

30 When the position of the covers is reversed, the pawl 9 will drop to the opposite end of the recess, which is beveled in such a manner that the pawl which is beveled correspondingly is moved inwardly and out of 35 engagement with the casing, so permitting the members to be separated.

A pin 10 projects from the post 4' into a slot 11 in the pawl 9. This slot is so formed as to limit the movement of the pawl 9 and 40 prevent the same from binding or wedging between the post and casing, but is of such a length to permit sufficient movement of the pawl, so that the projections from the outer surface thereof engage the projections on the 45 interior of the casing 8'. In this position the covers may be pressed together and will be held by the action of the pawl, as described.

The projections or serrations on the interior of the casing are preferably in the form 50 of a screw-thread or spiral, and the projections on the surface of the pawl are made correspondingly. The object of this is to permit of a further tightening of the covers after the same have been pressed down upon the 55 leaves. This may be effected by rotating the post carrying the pawl by the use of a screw-driver in the slot of the screw at the upper end of the said post, or a knurled head 60 may be provided to allow the same to be turned by hand or by other suitable means.

It will be noted that the device herein shown and described as an illustration of an operative embodiment of my invention is composed of a very small number of parts 65 and that such parts are of a simple construc-

tion and may be easily and cheaply manufactured. It will also be noted that the device when assembled is very compact in form and that the operating parts are self-contained within the same. I do not confine myself, however, to the exact details of construction shown and described, as it will be evident that various modifications and changes may be made therein to adapt the device to its several uses without departing from the scope of my invention.

What I claim is—

1. In a binder, the combination of a pair of telescoping members, one of said members having a projecting stop adapted to limit the movement of a pawl or dog toward its operative position, and a sliding pawl or dog adapted to engage said stop and also adapted to lock said telescoping members in position and to release the same when reversed. 85

2. In a binder, the combination of a pair of telescoping members, one of said members having a stop adapted to limit the movement of a pawl or dog toward its operative position, and a sliding pawl or dog adapted to engage said stop and also adapted to prevent the separation of said telescoping members. 90

3. In a binder, the combination of a pair of clamping members, a post having a recess therein attached to one of said members, a sliding pawl or dog provided with a serrated surface having a limited outward movement carried by said post in said recess in such a manner that the movement thereof in one direction is outward so that a portion thereof 100 will engage the inner surface of a casing, and a casing secured to the other of said clamping members and adapted to telescope over said post, substantially as described. 95

4. In a binder, the combination of a pair of telescoping members, one of said members having a recess therein and a projecting stop adapted to limit the movement of a pawl or dog toward its operative position, and a sliding pawl or dog adapted to engage said stop and also adapted to prevent the separation of said telescoping members. 105

5. In a binder, the combination of a pair of telescoping members, one of said members having a slot therein and a projecting stop 115 adapted to limit the movement of a pawl or dog toward its operative position, and a sliding pawl or dog positioned in said slot adapted to engage said stop and also adapted to prevent the separation of said telescoping members. 120

6. In a binder, the combination of a pair of clamping members, a post having a recess at the lower end thereof, said recess having an inclined portion forming a wall thereof, a 125 sliding pawl or dog provided with a serrated surface having a limited outward movement carried by said post and adapted to be operated by gravity on said inclined portion of said recess in said post and adapted to 130

gage the inner surface of a casing, and a casing having a threaded inner surface secured to the other of said clamping members and adapted to telescope over said post, substantially as described.

5. In a binder, the combination of a pair of clamping members, a post having a recess at the lower end thereof, said recess having an inclined portion adapted to engage a pawl or dog and throw the same into an operative position and also having an inclined portion adapted to engage said pawl or dog and throw the same into an inoperative position, a sliding pawl or dog provided with a serrated surface having a limited movement toward its operative position and adapted to alternately engage the aforesaid inclined portions of said recess and to be thrown into and out of engagement with the inner surface of 10 a casing by the action of gravity as the position of the same is reversed, and a casing adapted to telescope over said post, substantially as described.

8. In a binder, the combination of a pair of 25 clamping members, a post having a recess therein and having a stop projecting from a wall of said recess, a sliding pawl or dog carried by said post in said recess in such a manner that the movement thereof is limited by 30 said stop and adapted to engage the inner surface of a casing, and a casing secured to the other of said clamping members and adapted to telescope over said post, substantially as described.

35 9. In a binder, the combination of a pair of clamping members, a post having a recess therein and having a pin forming a stop projecting from a wall of said recess, a sliding pawl or dog carried by said post in said recess in such a manner that the movement thereof is limited by said stop and adapted to engage the inner surface of a casing, and a casing secured to the other of said clamping members and adapted to telescope over said post, substantially as described.

40 10. In a binder, the combination of a pair of clamping members, a post having a recess therein, said recess having a beveled portion forming a wall thereof adapted to engage a pawl or dog and throw the same outwardly into such a position that a portion thereof will engage the inner surface of a casing, a sliding pawl or dog provided with a serrated surface having a limited outward movement and adapted to engage said beveled portion of said recess and adapted to be thrown into engagement with the inner surface of a casing when operated by gravity, and a casing adapted to telescope over said post, substantially as described.

45 11. In a binder the combination of a pair of clamping members, a post having a recess at the lower end thereof, said recess having a beveled portion adapted to engage a pawl or dog and throw the same into engagement

with the casing and also having a beveled portion adapted to engage said pawl or dog and hold the same in an inoperative position in relation to said casing, a sliding pawl or dog provided with a serrated surface having 70 a limited movement toward its operative position and adapted to be operated by gravity in said recess and in conjunction with said beveled portion thereof into and out of engagement with a casing, and a casing adapted to telescope over said post, substantially as described.

12. In a binder, the combination of a pair of clamping members, a post having a recess therein, said recess having a wall thereof 80 adapted to engage a pawl or dog and move the same outwardly into engagement with a casing, a stop protruding from said wall of said recess and adapted to limit the movement of said pawl or dog in said recess, a 85 sliding pawl or dog adapted to be operated by gravity in conjunction with said wall of said recess and to have the movement thereof limited by said stop and adapted to engage the inner surface of a casing when moved to 90 its extreme position in one direction, and a casing adapted to telescope over said post, substantially as described.

13. In a binder the combination of a pair of clamping members, a post having a recess 95 therein, a stop attached to said post in said recess, a sliding pawl or dog carried by said post in said recess and having a portion thereof adapted to be engaged by said stop to limit the movement thereof toward its operative position and also having a portion thereof adapted to engage the inner surface of a casing, and a casing adapted to telescope over said post, substantially as described.

14. In a binder, the combination of a pair of clamping members, a post having a recess therein, a pin forming a stop attached to said post in said recess, a sliding pawl or dog carried by said post in said recess having a slot therein adapted to be engaged by said pin to 100 limit the movement thereof and also having a portion thereof adapted to engage the inner surface of a casing, and a casing adapted to telescope over said post, substantially as described.

15. In a binder-lock, in combination, a pair of clamping members, a post attached to one of said clamping members, a pin forming a guide carried by said post, a pawl or dog having a slot therein adapted to engage 110 said pin and to be guided thereby into an operative position when the members are in one position and into an inoperative position when the members are reversed, a casing secured to the other of said clamping members 120 and adapted to telescope over said post.

16. In a binder-lock, in combination, a pair of telescoping members, a pawl or dog carried by one of said members and adapted to engage the other of said members, and a 130

stop adapted to limit the movement of said pawl or dog toward its operative position.

17. In a binder-lock, in combination, a pair of telescoping members, and a pawl or dog carried by one of said members and adapted to engage a portion thereof to limit the movement of said pawl or dog toward its operative position.

18. In a binder-lock, in combination, a pair of telescoping members, a pin carried by one of said members, and a pawl or dog adapted to engage said pin to limit the movement thereof toward its operative position.

19. In a binder-lock, in combination, a pair of telescoping members, a pin carried by one of said members, and a pawl or dog having a slot therein, said slot being adapted to engage said pin to limit the movement of said pawl or dog toward its operative position.

Signed at New York, in the county of New York and State of New York, this 28th day of June, A. D. 1905.

FREDERICK A. CLEVELAND.
